TIME-RECORDER.

No. 870,061.

Specification of Letters Patent.

Patented Nov. 5, 1907.

Application filed February 5, 1906, Serial No. 299,429.

To all whom it may concern:

Be it known that we, DESERIE A. STOWELL and CHARLES T. HAWLEY, citizens of the United States, and residents of Gardner, in the county of Worcester and 5 State of Massachusetts, have invented an Improvement in Time-Recorders, of which the following description, in connection with the accompanying drawing, is a specification, like letters on the drawings representing like parts.

10 This invention relates to workmen's time recorders, and has for its object to provide a novel time recorder by which a record of one character may be made during a predetermined interval of time, and a record of a different character made during another predetermined interval of time, so that it will be possible to determine by a glance at the record sheet during which interval of time any particular record was made.

15 The device is especially useful in making plain and distinct the fact as to whether an employee is tardy or not, and when used in this way the time recorder is so adjusted that during the interval of time just prior to the time of arriving a record of one kind or character will be made on the sheet, while during the interval next succeeding the time of arrival the record which is 20 made on the sheet will be of a different kind or character.

In the present embodiment of our invention the record is made by perforating the record sheet with a marking punch, and the character of the mark is 25 changed by employing an auxiliary marking punch.

The device herein illustrated is so constructed that whenever a record is made both punches are actuated but during one interval of time, as, for instance, just prior to the arriving time, the auxiliary punch is in its 30 inoperative position, in which position it does not when actuated with the main marking punch make any record on the record sheet and the only record made is by said main marking punch, while during the subsequent interval of time, as, for instance, the interval 35 next succeeding the arriving time, said auxiliary punch is brought into operative position, in which position it perforates the sheet simultaneously with the main marking punch when said punches are actuated. The record made just prior to the arriving time, therefore, will consist of a single perforation, while the record made immediately after the arriving time consists of a double perforation.

We have herein shown our invention as applied to a machine of the general type illustrated and described 40 in co-pending application, Serial Number 296,642, filed January 18, 1906, by Deserie A. Stowell.

In the drawings, Figure 1 is a cross section through the marking device and cylinder for supporting the record sheet of a machine embodying our invention; 45 Fig. 2 is a detail of the auxiliary marking punch show-

ing it in its operative position; Fig. 3 is a vertical section through a time recorder embodying our invention showing the clock mechanism and part of the punching mechanism in elevation; Fig. 4 is a detail of the clock mechanism; Fig. 5 is a section on substantially the line $x-x$, Fig. 4, looking toward the top of the sheet; Fig. 6 is a section on the line $y-y$, Fig. 4, looking toward the left; and Figs. 7 and 8 are details of the controlling mechanism for the auxiliary punch showing it in different positions.

In the machine which has been selected herein to illustrate our invention 3 designates the cylinder on which the record sheet 4 is mounted.

5 designates the main marking punches which are carried on levers 6 which are pivotally mounted at 9 and are actuated by hand-pieces 7 projecting through the case 8 that incloses the operative parts of the machine.

The cylinder 3 is rotated by a suitable clock mechanism 10, and whenever any one of the finger-pieces 7 is moved from the full to the dotted line position, Fig. 1, or vice versa, the corresponding marking punch is elevated and caused to penetrate the record sheet 4.

The parts thus far described form no part of our present invention, but are features of the time recorder 80 illustrated and described in the above mentioned application to which reference may be had for a full and complete disclosure of the construction and operation of the parts above referred to.

In applying our invention to this type of time recorder we provide an auxiliary marking punch which is normally in inoperative position but which is thrown into operative position at predetermined intervals, and which when in operative position is actuated simultaneously with the main or principal punch to perforate 90 the record sheet. Preferably we will have as many auxiliary punches as there are main punches, that is, one for each of the thumb-pieces 7. The auxiliary punches herein illustrated are designated by 11, and they are all pivotally connected to a carrier 12 which is 95 pivoted to fixed standards, as at 14. The carrier 12 is also connected to a cranked portion of a crank-shaft 15, so that as the shaft is rotated said carrier moves the auxiliary punches into and out of operative position. The auxiliary punches are shown as situated directly above 100 the various levers 6, and the free end of each auxiliary punch rests on the corresponding lever 6, as best seen in Fig. 1, so that when the lever is rocked to actuate the main punch 5 and give it its penetrative movement the auxiliary punch is raised. Each auxiliary punch is 105 provided with a shank 16 curved on its underside and with a penetrating point 17.

When the carrier is in its elevated position, as shown in Fig. 1, the ends merely of the auxiliary punches rest on the levers 6, so that when any lever is operated the 110

- puncturing point of the corresponding auxiliary punch has a movement only substantially equal to that of the main punch which is insufficient to cause the auxiliary punch to penetrate the sheet 4. When, however, the 5 rock-shaft 15 is turned to lower the carrier into the position shown in Fig. 2, the auxiliary punches are brought into their operative position, in which position the convex portion of their curved under edges contacts with the levers 6. When in this position the movement of any lever 6 will give a much greater movement to the penetrating point of the corresponding auxiliary punch than when said auxiliary punch is in the inoperative position shown in Fig. 1 because in the former 10 position the lever 6 engages the auxiliary punch at a point much nearer its pivot than in the latter position. Consequently, when the auxiliary punches are in their operative position, as shown in Fig. 2, the rocking movement of any lever 6 will not only actuate the corresponding main punch to penetrate the record sheet but 15 said rocking movement will also cause the corresponding auxiliary punch to penetrate the record sheet 4 at the same time.
- The crank-shaft 15 may be controlled and turned by any suitable mechanism which will operate to move the 20 auxiliary punches from their operative to their inoperative position, and vice versa at the desired times. If for instance the arriving time of the employees is seven o'clock then the driving mechanism for the crank-shaft 15 will be so arranged that prior to seven o'clock 25 the carrier will be held in its elevated position and the auxiliary punches will occupy their inoperative position, as shown in Fig. 1, while the instant that seven o'clock arrives said crank-shaft will be turned into the position shown in Fig. 2, thereby moving the auxiliary 30 punches into their operative position. It will follow, therefore, that immediately preceding seven o'clock the record made on the record sheet 4 by the operation of any finger-piece 7 and the consequent actuation of the corresponding punches will be a single aperture 35 only, while at seven o'clock and immediately afterward the record made will be two apertures, one made by the main punch and the other by the auxiliary punch. It will be noted that in the present embodiment of our invention every time that any finger-piece 7 is operated 40 both of the corresponding punches will be actuated, but a single aperture or a double aperture will be punched in the record sheet according as at the time of the actuation of the punches the auxiliary punch is in its inoperative or its operative position.
- 45 In the present embodiment of our invention we have so constructed the driving apparatus for the crank-shaft 15 that the auxiliary punches are retained in their operative position for a short period only, say for fifteen minutes, after the arriving time; and at the end of said fifteen minute interval they will be restored to their inoperative position. The crank-shaft 15 is herein shown as extending into the clockwork mechanism of the recorder, and as having a gear 20 thereon which meshes with and is driven by a gear 21 on a counter-shaft 22.
- 50 The countershaft 22 is driven directly from a spring 23, one end of which is made fast to the shaft and the other end of which is connected to a collar 24 loose thereon, said collar 24 having gear teeth 25 which mesh 55 with and are driven from a gear 26 rigid with a gear 27

that is connected to the usual time train through a gear 36; the spring 23, therefore, is being constantly wound up and at predetermined intervals, say at seven o'clock and quarter past seven, and at one o'clock and a quarter past one, the shaft 22 is released by an escapement 70 mechanism and allowed to make substantially a half turn, thereby to turn the shaft 15 and throw the auxiliary punches into or out of operative position.

The escapement mechanism for the countershaft 22 is best seen in Figs. 4 to 8, and we have herein shown 75 it as comprising a main escapement and an auxiliary escapement. Fast on said shaft is a collar 30 to which one end of the spring 23 is secured and which is provided with a tail 31 normally engaging the underside of an escapement or controller 32, herein shown as a disk 80 having one or more slots 33 therein and a projection 34 adjacent each slot. The controller 32 has rigid therewith a gear wheel 35 which meshes with and is driven by a gear 36 that in turn is driven by the usual time train, as above stated. The tension of the spring 23 85 normally keeps the tail 31 against the underside of the controller disk 32, and the latter by its engagement with said tail holds the shaft 22 against rotation, but when during the rotation of said disk a slot 33 comes opposite the tail, the shaft 22 is released and will be rotated by the spring 23, the tail passing through the slot during this operation.

In order to prevent the crank-shaft 15 from having more than a partial rotation sufficient to carry the auxiliary punches from their inoperative to their operative 95 position, the collar 30 is provided with a finger or projection 38 shorter than the tail 31, which finger or projection is adapted to engage the underside of the ear or projection 34 of the controller disk when the shaft 22 has made substantially a half revolution, as seen in 100 Fig. 8. The half revolution of the shaft 22 from the position shown in Fig. 7 to that shown in Fig. 8 carries the auxiliary punches from their inoperative position, as shown in Fig. 1, to their operative position, as shown in Fig. 2, and the engagement of the finger 38 with the 105 projection 34 holds the said auxiliary punches in their operative position. The length of time that the punches remain in their operative position depends upon the width of the projection 34, and while this may be of a width to hold the auxiliary punches in 110 their operative position for any predetermined interval of time, we have herein illustrated it of such a width as to maintain them in such position for a fifteen minute interval of time. After the controller disk 32 has rotated sufficiently so as to be disengaged from the projection 38, the shaft 22 will make another half revolution to bring the tail 31 against the underside of the controller disk, that is, it will rotate from the position shown in Fig. 8 to that shown in Fig. 5, thus carrying the auxiliary punches back into their inoperative position where they will remain until another slot 33 comes into alignment with the tail 31. By making the desired number of slots 33 and projections 34 on the controller disk the auxiliary punches may be moved from their inoperative to their operative position and 115 vice versa at any desired intervals of time. In the embodiment of the invention herein shown the controller disk is so constructed that this change will occur at seven and one o'clock respectively. The movement of the disk 32 is necessarily quite slow, and if 120 125 130

said disk alone were relied upon to release the spring-impelled shaft 22 the clock-work would have to be made very carefully and delicately in order that the release of said shaft by this escapement mechanism 5 should occur precisely at seven o'clock and one o'clock.

It is quite important in our invention that the spring-impelled shaft 22 should be released exactly at the times desired, in the present instance exactly at seven o'clock and one o'clock and in order to provide for this 10 accurate release of said shaft we employ in addition to the main escapement, including the controller-disk 32, an auxiliary escapement constructed so as to insure the release of the shaft at exactly the proper time. This auxiliary escapement is shown as a screw-cam 40 15 mounted on a shaft 41, which has a gear 42 thereon that meshes with and is driven by a gear 43 on the arbor that carries the minute hand of the clock. The shaft 22 has fast thereto an arm 44 carrying a finger 45 which is adapted to engage the screw-cam 40.

20 When the parts are in the position shown in Fig. 5, the finger 45 is just above the screw-cam, but the instant that a slot 33 registers with the tail 31, the spring 23 gives the shaft 22 an initial turning movement to bring the finger 45 against the screw-cam, as in Fig. 7, this 25 movement being sufficient to carry the finger 31 through the slot 33. As the screw-cam 40 is turned by the clock-work, the arm 44 gradually moves downward until the finger 45 passes off from the screw-cam. When this occurs the spring 23 immediately completes 30 the half rotation of the shaft 22 and brings the finger 38 against the underside of the projection 34, as seen in Fig. 8. The screw-cam 40 rotates at a much greater speed than the controller-disk 32, and, therefore, the time when the finger 45 is released from said cam and 35 consequently the moment when the shaft 22 is released by the auxiliary escapement can be much more accurately controlled than if dependence were placed entirely upon the disk 32. The screw-cam 40 also acts as a retarding device to retard the turning movement 40 of the collar 30 sufficiently so that during the time that the collar 30 is turning from the position shown in Fig. 7 to that shown in Fig. 8 the controller disk 32 will have to be moved sufficiently to carry the notch or slot 33 out of alinement with the projection 38. As a result 45 when the shaft 22 makes its half turn from the position shown in Fig. 7 to that shown in Fig. 8, said projection 38 is brought up against the projection 34 of the disk 32. It will thus be seen that the release of the spring-impelled shaft 22 is dependent on the action of two different 50 escapements, one, the main escapement comprising the controller-disk 32 and the other, the auxiliary escapement comprising the screw-cam 40. The main escapement partially releases said shaft and places it under the control of the auxiliary escapement 55 at approximately the desired time; and the auxiliary escapement operates to release said shaft at exactly the desired time.

We have also incorporated in our device a visual signal by means of which a person can tell from a glance 60 on the time-recorder whether he is late or not. This visual signal is in the form of a semaphore or a disk with the word late or some equivalent word marked thereon which is normally behind a screen, but which is thrown out from the screen into sight at predetermined intervals. 65 Preferably this signal is connected to the shaft

15, so that it will operate in unison with the carriage carrying the auxiliary marking punches. As herein illustrated, the signal is designated by 90 and is carried by a swinging arm 91 which is connected by means of a link 92 with a crank 93 fast on a gear 94 meshing with a gear 95 fast on the shaft 15. Whenever the shaft 15 is turned, to move the auxiliary punches from their inoperative to their operative position, such movement will swing the signal 90 from the full to the dotted line position Fig. 3, and in the dotted line position it stands 70 in front of an opening in the casing 8 so that it can be seen. With this arrangement, it will be noted that the "late" signal is displayed whenever the auxiliary punches 75 11 are in their operative position, but is hidden from sight when they are in their inoperative position. 80

It is not essential to our invention that the change in the character of the mark which is made during the interval of time following a definite period should be accomplished by using an auxiliary punch.

The mechanism illustrated herein is one embodiment 85 only of our invention and has been selected from various different embodiments thereof for the purpose of illustrating the principle of the invention; and although the selected form of the invention is capable of making records of two different characters only the invention is not limited to such a construction. 90

Having fully described my invention what I claim as new and desire to secure by Letters Patent is:—

1. In a time recorder, the combination with mechanism to make perforations of different characters in a record sheet and manually-operative actuating means therefor, of time controlled means separate from said mechanism to determine the interval of time during which each of the different characters of perforations may be made by said manual operation of the actuating means. 95

2. In a time recorder, the combination with means to support a record sheet, of a main marking device adapted at all times to make a complete time record on said sheet, an auxiliary marking device normally in inoperative position, means for actuating said marking devices, and means 100 separate from said actuating means to move the auxiliary marking device to carry it into marking position. 105

3. In a time recorder, the combination with means to support a record sheet, of a main marking device adapted at all times to make a complete time record on said sheet, 110 an auxiliary marking device, actuating means for said marking devices, and automatic means separate from said actuating means to move the auxiliary marking device to carry it into and out of operative position.

4. In a time recorder, the combination with means to support a record sheet of a main marking device adapted of itself at all times to make on said sheet a complete time record, actuating means for said marking device, an auxiliary marking device normally in inoperative position, and means to move the auxiliary marking device relative to 115 the main marking device to carry said auxiliary marking device into operative position. 120

5. In a time recorder, the combination with means to support a record sheet, of a main marking device adapted at all times to make a complete time record on said sheet, actuating means for said marking device, an auxiliary marking device normally out of operative position, and automatic means to throw it into operative position at 125 predetermined intervals of time.

6. In a time recorder, the combination with means to support a record sheet, of a main marking device adapted at all times to make a complete time record on said sheet, an auxiliary marking device, automatic means to carry the auxiliary marking device into and out of operative position, and manually-operative means to move the marking 130 devices to cause the record to be made. 135

7. In a time recorder, the combination with means to support a record sheet, of a main marking device adapted

- at all times to make a complete time record on said sheet, an auxiliary marking device, manually-operative means to move the marking devices to cause the record to be made, and means to move the auxiliary marking device into and out of operative position. 5
8. In a time recorder, the combination with means to support a record sheet of a main marking device adapted at all times to make a complete time record on said sheet, a normally-inoperative auxiliary marking device, and automatic means to throw the auxiliary marking device into operative position at a definite time and to maintain said marking device in operative position for a definite interval. 10
9. In a time recorder, the combination with means to support a record sheet, of a main marking punch adapted at all times to make a complete time record on said sheet, an auxiliary marking punch normally inoperative position, means for manually actuating said punches, and automatic means to move the auxiliary punch into and out of operative position at a definite time. 15
20. 10. In a time recorder, the combination with means to support a record sheet, of a main marking punch normally in operative position, an auxiliary marking punch normally in inoperative position, means for moving said punches simultaneously toward the record sheet, and means to shift the position of the auxiliary punch relative to the main punch at predetermined times to carry said auxiliary punch into operative position. 25
11. In a time recorder, the combination with means to support a record sheet of a main marking punch, an auxiliary marking punch, manual means for moving the punches simultaneously toward the record sheet, the main marking punch being in position to penetrate the sheet during each movement, and the auxiliary marking punch being normally in position not to penetrate the sheet during such movement, and means to move the auxiliary punch relative to the main punch to carry said auxiliary punch into operative position so that it will penetrate the sheet. 30
40. 12. In a time recorder, the combination with a record sheet, of a main marking punch and an auxiliary marking punch, means to actuate said punches simultaneously, the main punch normally being in position to penetrate the sheet when actuated, and the auxiliary punch normally being out of position to penetrate the sheet, and time-controlled means to carry the auxiliary punch into position to penetrate the sheet when actuated. 45
13. In a time recorder, means to support a record sheet, a main marking device, an auxiliary marking device adapted to be actuated by the main marking device, and means to throw the auxiliary marking device into and out of operative position. 50
55. 14. In a time recorder, means to support a record sheet, a main marking device, an auxiliary marking device adapted to be actuated by the main marking device, and automatic means to throw the auxiliary marking device into operative position at a predetermined time and out of operative position after a predetermined interval. 60
65. 15. In a time recorder, means to support a moving record sheet, a main marking punch, a pivoted lever for operating said punch, and an auxiliary marking punch in contact with said lever, whereby said auxiliary marking punch is moved by the movement of the lever in giving the main marking punch its penetrative movement. 70
75. 16. In a time recorder, means to support a moving record sheet, a main marking punch, a pivoted lever for operating said punch, an auxiliary marking punch in contact with said lever, whereby said auxiliary marking punch is moved by the movement of the lever in giving the main marking punch its penetrative movement, and automatic means to throw the auxiliary marking punch into and out of operative position. 80
17. In a time recorder, the combination with a marking device and means to actuate it, of means to move said marking device into and out of operative position, and a controller to control the time of operation of said means. 85
75. 18. In a time recorder, the combination with a marking device and means to actuate it, of automatically-operative means to move said marking device into and out of operative position, and a controller to control the time of operation of said means. 90
80. 19. In a time recorder, the combination with a plurality of marking devices, of a spring to move said marking devices simultaneously into and out of operative position, and automatic means to maintain said spring under tension. 95
20. In a time recorder, the combination with clock work mechanism, of a plurality of marking devices, a spring to move said marking devices simultaneously into and out of operative position, and means operated by the clock mechanism to maintain said spring under tension. 100
21. In a time recorder, the combination with a marking device and means for actuating it, of automatically-operative means to move said marking device into and out of operative position, and a time controller to govern the time of operation of said means. 105
22. In a time recorder, a marking device, a spring-impelled shaft to move said marking device into and out of operative position, a disk controller having a notch, an arm on said shaft normally held against the controller by said spring, and means to move the controller, whereby when the arm comes opposite the notch the spring operates to turn the shaft. 110
23. In a time recorder, a spring-impelled shaft, a controller having a notch, an arm on the shaft normally held against the controller by the spring, and means to move the controller. 115
24. In a time recorder, a spring-impelled shaft, a controller having a notch and a projection, two oppositely-disposed arms on said shaft, one of which is normally held against the controller by the spring and the other of which is adapted to engage the projection when the shaft has made a partial turn, and means to move the controller. 120
25. In a time recorder, a spring-impelled shaft, a controller having a notch, an arm on the shaft normally held against said controller by the spring, means to move the controller, thereby to bring the notch into engagement with said arm to permit the arm to pass through the notch, and means to retard the turning movement of the shaft. 125
26. In a time recorder, a marking device, a spring-impelled shaft for shifting the position of the marking device, a controller having a notch and a projection, two oppositely disposed arms on said shaft, one of which is normally held against the controller by the spring, and means to move the controller to bring the notch opposite said arm, thereby to permit the arm to pass through the notch and the shaft to make a partial turn to bring the other arm against the projection. 130
27. In a time recorder, a marking device, a spring-impelled shaft for shifting the position of the marking device, a controller having a notch and a projection, two oppositely disposed arms on said shaft, one of which is normally held against the controller by the spring, means to move the controller to bring the notch opposite said arm, thereby to permit the arm to pass through the notch and the shaft to make a partial turn to bring the other arm against the projection, and means to retard said turning movement of the shaft. 135
28. In a time recorder, the combination with a marking device and means for actuating it, of a shaft for moving said marking device into and out of operative position, and time-controlled means to rotate said shaft. 140
29. In a time recorder, the combination with a marking device and means for actuating it, of a shaft for moving said marking device into and out of operative position, and time-controlled means to turn said shaft intermittently. 145
30. In a time recorder, the combination with a main marking device, an auxiliary marking device, and means for actuating said marking device, of a shaft to move said auxiliary marking device into and out of operative position, and time-controlled means to give said shaft an intermittent turning movement. 150
31. In a time recorder, the combination with a main marking device, an auxiliary marking device, and means to actuate said marking device, of means to move said auxiliary marking device into and out of operative position, said means including a spring-impelled shaft normally held against turning movement, and time-controlled means to release said shaft at definite intervals. 155
32. In a time recorder, the combination with a marking device and means to actuate it, of automatically-operative 160

marking-device-controlling means, to move said marking device into and out of marking position and two co-operating escapements controlling the time of operation of said means.

5 33. In a time recorder, the combination with a marking device, and means to actuate it, of automatically-operative marking-device-controlling means, to move said marking device into and out of marking position and two successively operating co-operating escapements controlling the 10 time of operation of said means.

15 34. In a time recorder, the combination with a marking device, and means to actuate it, of automatically-operative, marking-device-controlling means, to move said marking device into and out of marking position and two co-operating escapements of different degrees of sensitiveness 20 controlling the time of operation of said means.

25 35. In a time recorder, the combination with a marking device, and means to actuate it, of automatically-operative means, to move said marking device into and out of marking position a main escapement normally holding the automatically-operative means inactive but adapted to partially release the same at a definite time, and an auxiliary escapement to effect the complete release of said means.

30 36. In a time recorder, the combination with a marking device, and means to actuate it, of automatically-operative means, to move said marking device into and out of marking position a main escapement normally holding said means inactive but adapted to release said means at a definite time, and an auxiliary escapement to control the means when released by the main escapement.

37. In a time recorder, a spring-impelled marking-device-controlling shaft, a marking device controlled as

to its position thereby, means to operate the marking device, and two co-operating escapements controlling the 35 time of operation of said shaft, said escapements acting successively and each operating to lock the shaft against forward movement for a certain period.

38. In a time recorder, manually-operative means to make perforations of different characters in a record sheet, automatic means to determine the interval of time in which it is possible to make any character or record, and a signal operated by said automatic means by which the character of the perforations made at any time may be determined. 40

45 39. In a time recorder, a marking device, means to throw the marking device into and out of operative position, a casing inclosing said marking device and provided with a sight opening, and a movable signal operatively connected to said means and adapted to be thrown into 50 and out of line with said sight opening thereby.

40. In a time recorder, a main marking device, an auxiliary marking device, means to throw the auxiliary device into and out of operative position, a casing inclosing said parts and provided with a sight opening, and a 55 movable signal operatively connected to said means and adapted to be thrown into and out of line with said sight opening thereby.

In testimony whereof, we have signed our names to this specification, in the presence of two subscribing witnesses. 60
